UNITED STATES PATENT OFFICE.

OSCAR P. OSTERGREN, OF NEW YORK, N. Y., ASSIGNOR TO THE OSTERGREN MANUFACTURING COMPANY, OF NEW JERSEY.

HOT-AIR ENGINE.

SPECIFICATION forming part of Letters Patent No. 671,526, dated April 9, 1901.

Application filed May 11, 1900. Serial No. 16,248. (No model.)

To all whom it may concern:

Be it known that I, OSCAR P. OSTERGREN, a subject of the King of Sweden and Norway, and a resident of Bedford Park, borough of Bronx, city and State of New York, have invented certain new and useful Improvements 5 in Hot-Air Engines, of which the following is a specification.

My invention relates to hot-air engines employing liquid fuel and compressed air and burning the same in the cylinder for expansive effect; and the principle features of novelty are the means and manner by which the air and fuel are mixed and admitted to the 15 expansion-cylinder, means of effecting the combustion, means of compressing, cooling, and preheating the air, and means of storing compressed air for use in starting and operating the engine prior to the production of 20 heat necessary to the regular operation, all as hereinafter described, reference being made to the accompanying drawings, in which—

Figure 1 represents a vertical longitudinal section of my improved engine, with a cooling attachment for the compressed air. Fig. 2 is a side elevation with the principal part of the cooling attachment detached. Fig. 3 is a plan view of a pair of engines and the cooling attachment, with one of the engines in 25 horizontal section and parts of the compressed-air and fuel-storage tanks broken off. Fig. 4 is an enlarged detail in the same section as Fig. 1 for more clearly representing the admitting, igniting, and fuel-burning devices. Fig. 5 is an enlarged end view as 30 seen looking from the left hand of Fig. 4.

The cylinder is represented at *a*. It is about double the length of the stroke of the piston. The interior part *b*, comprising about 40 half the length of the bore, is bored and fitted for coaction with the piston *c*. The other interior half-part *d* of the cylinder is slightly larger than part *b* and need not be bored or fitted. The piston *c* has an extension *f* of 45 about the length of the unfitted part *d* of the cylinder and working in free space therein. The piston has a trunk extension *g* of smaller diameter than the piston and of greater length than the length of the stroke of the piston 50 and working in a tubular guide *h*, in which, like the piston, it is to be packed for utilizing the parts on that side of the piston for compressing air, *i* being an induction-valve, and *j*

an eduction-valve. The piston *c*, its extension *f*, and trunk *g* are preferably of hollow structure for economy of weight and material. The connecting-rod *k* is attached to a block *l*, inserted in the outer end of the hollow trunk *g* and is connected to the crank *m* of the shaft *n* in the usual manner. 55

The cover *o* of the rear end of the cylinder *a* has on its exterior side a mixing-chamber *p* for air and oil, into which the air is supplied through inlet-valve *q*, and oil is supplied through an injector *s*, the mixture being injected by the force of the compressed air through the orifice *t* into a cavity *u*, in front of which is a ball *v* for spreading the mixture and igniting it, said ball being in the location where the heat of combustion is greatest, so 60 as to be quickly heated after the starting of the engine, and to be kept so highly heated as to promptly ignite the periodically incoming jets of the fuel elements. The ball-spreader 65 thus located in the cavity and the cavity being 70 in practical conformity with the shape of the ball and a little larger, affords limited space between two confronting hot surfaces of a character adapted for the most effective 75 spreading and distributing the oil and impingement of the particles on the hot surfaces 80 for ignition. The cavity *u*, in which the ball is arranged, is formed in a boss *w*, supported on the inner side of the cover *o* by a contracted neck *x*, the small size of which reduces 85 heat-conducting material, so that less heat is wasted through the cover than if the connection were the full size of the boss, and the ball is supported in the cavity by arms *y* of the ball joining the boss at the mouth of the 90 cavity. The part *f* of the piston has a recess *z* in the end, affording space for the projecting boss and ball, avoiding conflict when the piston moves in that direction. This extension of the igniting bodies far into the cylinder-space and their isolation by the contracted 95 supporting-neck is an important element of efficiency in insuring reliability of the igniting apparatus.

The injector has a reciprocating needle-valve *2*, which is opened at the proper time by a lever *3* on the rock-shaft *4*, said shaft being actuated by a cam *5* on the stem of valve *q*, and a lever *6* of the rock-shaft to open said needle-valve, and a spring *7* closes it. 100 105

The oil or other liquid fuel is supplied to the

injector from the reservoir 8 through the pipe 9.

Compressed air is normally supplied to the injector through valve *q* from the jacket 14, 5 surrounding the cylinder *a*, through which it is caused to flow for keeping the heat of the cylinder down to practicable limits and for being heated and expanded and to facilitate its combustion in the cylinder.

10 When the engine is to be used for automobile purposes, where water is not available for cooling the cylinder, the air from the compressor is discharged into the reservoir, from which it circulates through cooling-coils 15, 15 which discharge into a collecting-header 16, and therefrom enters at 17 into the cooling-jacket 14 of the cylinder, and thence passes to the valve *q*, and being thus cooled before entering the jacket suitably protects the cylinder, but where water is available the cooler may be dispensed with and water employed, at least in the part of the jacket surrounding the piston-trunk guide and the part *b* in which the piston works, it being still desirable to have the ingoing air preheated, which may be done by causing it to pass through that part of the jacket surrounding part *d* of the cylinder, for which said jacket will be suitably partitioned at about the middle of 30 the length of the cylinder.

The exhaust-valve 18 is located at the middle of the length of the cylinder or thereabout, where the free space between the piston extension *f* and the larger part *d* of the 35 cylinder terminates, so that return of the cooled and expanded gases to the place of combustion, and thereby chilling the parts, as when the exhaust-valve is in the locality of the igniting parts, is prevented, which would injuriously affect the efficiency of the engine, 40 and the escaping gases are brought into close contact with the cylinder-wall by passing between it and the extension of the piston and caused to pass in the opposite direction of the 45 compressed air going to the outlet-valve, so that the air absorbs more of the heat of the escaping gases. This provision, combined with the inward extension and isolation of the igniting parts, affords additional means of insuring igniting temperature.

The valves *q* and 18 are all of the rocking type and are all coupled by rod 19 with the sliding link 20, the ends of which are respectively coupled to eccentrics 21 on the shaft *n* 55 in the common "link-motion" device, by which the action of the valves may be varied and the motion of the engine reversed, as usual with such gear.

60 A funnel-mouthed filler 22 is provided for charging the fuel-reservoir 8 with oil, said filler having a stop-cock 23 to retain air under compression for feeding the oil against the pressure in the mixer, said reservoir being in communication with the air-reservoir

65 10 through a pipe 24. A hand-pump 25 is provided for priming the reservoirs through

pipe 26 when they are lacking in pressure to begin with.

If a volatile liquid is used, such as benzene or gasolene, the temperature of the air will 70 be sufficient for ignition; but if kerosene is used it will be necessary to ignite the first few charges by means of electric sparks, as indicated by the electric device 26 of common use or by artificially heating the mixing-chamber 75 *p* from the outside.

What I claim as my invention is—

1. The combination with the cylinder, piston, and mixing-chamber, of the igniting-cavity formed in an inward and isolated extension of the cylinder-cover, the spreading and igniting ball located in said cavity, and means for injecting the fuel elements onto the ball through the center of the cavity. 80

2. The combination with the cylinder, piston, and mixing-chamber, of the igniting-cavity formed in an inward and isolated extension of the cylinder-cover, spreading and igniting ball located in said cavity, means for injecting the fuel elements onto the ball 85 through the center of the cavity, and an exhaust-valve for escape of the spent gases at the end of the range of their impelling action. 90

3. The combination with the cylinder and piston, of means for injecting compressed 95 air and oil and burning and expanding them on one side of the piston for impelling it, an air-heating and cylinder-cooling jacket surrounding the cylinder, means for compressing air on the other side of the piston, a compressed-air reservoir in connection with the air-compressing devices for being charged, and a cooler for the compressed air in connection with said reservoir for the circulation of the air through it, and also in connection with 105 the air-heating and cylinder-cooling jacket for supplying the compressed and cooled air to the injecting devices therethrough. 110

4. The combination with the cylinder and piston, of means for injecting compressed 110 air and oil and burning and expanding them on one side of the piston for impelling it, an air-heating and cylinder-cooling jacket surrounding the cylinder, means for compressing air on the other side of the piston, a compressed-air reservoir in connection with the air-compressing devices for being charged, and also in connection with the injecting devices for starting the engine by direct action of compressed air, and a cooler for the compressed air in connection with said reservoir for the circulation of air through it, and also 120 in connection with the air-heating and cylinder-cooling jacket for supplying the compressed air through said jacket to the injecting devices after starting. 125

Signed by me at New York, N. Y., this 3d day of May, 1900.

OSCAR P. OSTERGREN.
